UNITED STATES PATENT OFFICE.

WALTER W. WARING, OF STERLING, KANSAS.

POCKET INDEX-FILE.

1,272,155.

Specification of Letters Patent.

Patented July 9, 1918.

Application filed February 25, 1918. Serial No. 220,087.

To all whom it may concern:

Be it known that I, WALTER W. WARING, a citizen of the United States, residing at Sterling, in the county of Rice and State 5 of Kansas, have invented certain new and useful Improvements in Pocket Index-Files, of which the following is a specification.

This invention relates to pocket files of the accordion type bearing identification or 10 index letters on the back walls of the respective pockets, and my object is to produce a file of this character of such construction that the opening or spreading of a pocket or pockets so affects the back wall 15 or walls thereof as to more prominently display the identifying letter or letters thereof and thus facilitate the filing of letters or the like in the file or reference to the contents thereof. A further object is to produce 20 a file of this character which when opened, tends to remain in that condition and in an upright position, and thereby makes for rapidity and accuracy of filing.

With these general objects in view, the 25 invention consists in certain novel and useful features of construction and combinations of parts as hereinafter described and claimed; and in order that it may be fully understood, reference is to be had to the accompanying drawing, in which:—

Figure 1, is a fragmentary side view of a pocket index file embodying the invention.

Fig. 2, is a top plan view of the same.

Fig. 3, is a vertical section taken through 35 one end of a pocket, on the line III—III of Fig. 2.

Fig. 4, is a similar view taken through the side of the file between adjacent pockets, on the line IV—IV of Fig. 2.

Fig. 5, is a perspective view of the upper 40 part of the file.

Fig. 6, is a similar view of a part of one of the sides of the file.

In the said drawing, 1 indicates a strip of 45 heavy paper or the like, folded accordion like, to form a plurality of V shaped pockets 2, of which 3 indicates the back walls and 4, the front walls, the walls 3, being horizontally creased to provide bending lines 5 near and parallel with their upper edges and equipped above said bending lines with index characters or the like, such as the letters of the alphabet, not shown, because common in this class of files, each character

identifying a particular pocket. The series 55 of pockets are of integral formation though it is obvious they may be composed of strips of material bound together to constitute a unit instead of being formed from a single folded strip as shown for convenience 60 and clearness of illustration.

The sides 6 of the file are likewise more clearly and conveniently shown as formed from single strips of material folded accordion like to form alternately arranged 65 V shaped folds 7, and inverted V-shaped folds 8, the latter being truncated at their upper ends, the junction lines of said folds coinciding with and being secured to the ends of the walls 3 and 4 of the pockets so 70 that opening and closing movement of the latter shall effect lateral expansion or contraction of the end folds 7 and 8, it being noted in this connection that the upper edges of the sides occupy a plane near and 75 preferably slightly below that of the bending lines 5, to avoid interfering with folding and unfolding action of the back walls on said lines as the pockets are respectively 80 opened or closed, the folding action on said lines causing the character-bearing portions of the pockets to face upwardly to a greater extent than the parts of said walls below said lines, and thus bring the said characters to positions where they can be seen to better 85 advantage.

The central fold lines 9, of folds 7 which constitute the sides of the pockets, incline downwardly and outwardly to and intersect with the bottom of the file where the junction lines of the folds 7 and 8 meet or merge, (see Fig. 6) the inclination being greatest when the pockets are fully collapsed or closed and very slight when the pockets are fully opened, this being noted by reference 95 to Figs. 1 and 2, which show several pockets nearly closed and others about fully opened.

The central fold lines 10 of the folds 8, which constitute the sides of the file between the pockets, incline downwardly and inwardly or reversely to fold lines 9, and both sets of fold lines 9 and 10 stand in perpendicular planes as clearly shown in Fig. 1.

The degree to which the pockets open depends on the depth of folds 7, and the degree 105 to which the index-bearing portions of the back walls of the pockets fold or turn upward depends on the depth of folds 8, and

the leverage action thereof applied on the walls of the pockets at or below the bending lines 5.

The general tendency of files of this class 5 is to close, thus concealing the index and making it necessary to open the file preliminary to identifying the desired pocket. The tendency of this file, due to the fact that the creases 9 and 10 of the pockets are 10 substantially vertical when the file is open, is to stay open and hence maintain the file in an upright position and provide for maximum visibility of the index at all times and therefore make for rapid and accurate filing.

15 From the above description, it will be apparent that I have produced a pocket index file embodying the features of advantage set forth as desirable in the statement of the object of the invention, and while I have 20 illustrated the preferred construction, it is apparent that the file is susceptible of modification in minor particulars without departing from the principle of construction involved.

25 I claim:

1. A file comprising a series of pockets, the front and back walls whereof diverge upwardly, each back wall having near its upper edge a longitudinal crease to facilitate bending, and sides connected to the ends of said walls and formed with alternately disposed V-shaped and inverted V-shaped folds, the V-shaped folds projecting into and forming the ends of the pockets 30 and the inverted V-shaped folds projecting inward between and forming the sides of the spaces between adjacent pockets.

2. A file comprising a series of pockets, the front and back walls whereof diverge 40 upwardly, each back wall having near its upper edge a longitudinal crease to facilitate bending, and sides connected to the ends of said walls and formed with alternately disposed V-shaped and inverted V-shaped 45 folds, the V-shaped folds projecting into and forming the ends of the pockets and the inverted V-shaped folds projecting inward between and forming the sides of the spaces between adjacent pockets; the walls 50 of the pockets projecting to a plane higher than the sides by an amount at least equal

to the distance between the horizontal planes of the top of said walls and said creases of the back walls of said pockets.

3. A file comprising a series of pockets, 55 the front and back walls whereof diverge upwardly, each back wall having near its upper edge a horizontal crease to facilitate bending, and sides connected to the ends of said walls and formed with alternately disposed V-shaped and inverted V-shaped folds, the V-shaped folds projecting into and forming the ends of the pockets and the inverted V-shaped folds projecting inward between and forming the sides of the 60 spaces between adjacent pockets; the inverted V-shaped folds being truncated at their upper ends, and the walls of the pockets projecting to a plane higher than the sides by an amount at least equal to the 65 distance between the horizontal planes of the top of said walls and said creases of the back walls of said pockets.

4. A file comprising a series of pockets, the front and back walls whereof diverge 75 upwardly, each back wall having near its upper edge a horizontal crease to facilitate bending, and sides connected to the ends of said walls and formed with alternately disposed V-shaped and inverted 80 V-shaped folds, the V-shaped folds projecting into and forming the ends of the pockets and the inverted V-shaped folds projecting inward between and forming the sides of the 85 spaces between adjacent pockets; the inverted V-shaped folds being truncated at their upper ends, and the walls of the pockets projecting to a plane higher than the sides by an amount at least equal to the 90 distance between the horizontal planes of the top of said walls and said creases of the back walls of said pockets, the central lines of the V-shaped folds sloping downward and outward and the central lines of the inverted V-shaped folds sloping downward and inward when the pockets are partially or wholly closed and extending substantially vertical when the pockets are 95 fully opened.

In testimony whereof I affix my signature.

WALTER W. WARING.
